UNITED STATES PATENT OFFICE.

CARL OLSON, OF CANTON, OHIO, ASSIGNOR TO THE CANTON ART METAL COMPANY.

METAL FURNITURE.

1,148,330.

Specification of Letters Patent. Patented July 27, 1915.

Application filed May 14, 1914. Serial No. 838,614.

To all whom it may concern:

Be it known that I, CARL OLSON, a subject of the King of Sweden, and residing at Canton, in the county of Stark and State 5 of Ohio, have invented certain new and useful Improvements in Metal Furniture, of which the following is a specification, reference being had therein to the accompanying drawing.

10 My invention relates to improvements in metal furniture, and in particular to an improved manner of constructing the tops or flat wearing surfaces of the said furniture.

Another object of the present invention 15 is the novel manner of securing coverings or wearing surfaces to the tops of metal furniture, such as desks, tables, etc., in such a way that the top of finished furniture at every point is smooth and presents an attractive appearance.

20 Another object of my present invention is to so construct the holding means for the cover or wearing surface that it also forms a binding therefor of an attractive finished appearance and in which the holding or clamping means is concealed.

So far as I am aware, devices of the character to which this invention relates have heretofore been so constructed that some 30 part at least of the clamping member is visible, and thus indicate that the binding is a part separate from the metallic body or top of the furniture. The construction of my improvement is such that all of the 35 clamping means is concealed and the holding binding has the appearance of being formed as an integral part of the metal body of the furniture.

In the accompanying drawings, Figure 1 40 is a perspective sectional view of the top or wearing surface of a piece of metal furniture with my improvement applied thereto. Fig. 2 is a sectional view on the line 2—2 of Fig. 1. Fig. 3 is a detached perspective view of the two parts which comprise my present improvement. Fig. 4 is a sectional view showing a slightly modified construction of my improvement.

45 In carrying out my present improvement, the top of the metal furniture is made of a form, such as heretofore used, and it comprises a top body 1, which is provided with a binding flange 2. This flange 2 preferably extends substantially all around the top of

the body of the top portion, though it is 55 not absolutely essential for the application thereto of my present improvement.

My present improvement relates to a binding 3 for the top 1, and this binding performs the double function of a binding and 60 a clamping or holding means for the wearing surface 4. This wearing surface 4 may be made of any suitable material, such as heavy linoleum, glass, etc., and when composed of linoleum it is preferably cemented 65 throughout its surface to the metal top or body-portion 1.

My improvement consists generically in providing the binding 3 at its inner side with an upper longitudinal groove 5, and a lower 70 longitudinal groove 6, thus forming a track or channel-way for the clamping device 7. This clamping member 7 is in the form of a head or block, as shown in Fig. 3, of a thickness to freely slide in the channels or 75 grooves 5 and 6. In the form shown in Figs. 1, 2 and 3, a screw 8 has its stem screw-threaded into the head 7, and the head 9 of the screw countersunk therein. In this way the screw is carried by the head 7. The 80 stem of the screw is made sufficiently long to pass through vertically elongated openings 10, which are formed in the depending flange 2 of the body or top 1 and to receive a clamping-nut 11, as shown in Fig. 2. 85

The lower groove 6 of the binding 3, is formed by an L-shaped flange 12, which has its walls extending at right-angles, whereas the upper groove 5 is formed by the horizontal or right-angular extending flange 13 90 and the inwardly and downwardly inclined wall 14. Preferably, the lower edge 15 of this wall 14, extends downward parallel with the outer wall of the binding 3 and at right-angles to the top flange 13. As shown 95 in Figs. 2 and 4, the downwardly extending flange 15 and the upwardly extending flange 16 are in vertical alinement so that with their outer faces resting against the outer face of the flange 2, the binding 3 is supported at right angles to the top of the body 1. However, I desire it understood that this may be varied if it is desired to have the binding 3 extend at an angle outward or inward in respect to the top or body-portion 100 1. By reference to Figs. 2 and 4, it will be observed that the inclined flange 14 stops at a point in the plane of the outer surface

of the body-portion 1 and the binding flange 15 engages the outer surface of the flange 2.

By means of this construction a suitable number of clamping heads 7 are placed in 5 the grooves 5 and 6 of the binding and they are moved therein to points in alinement with the openings 10 and pass therethrough and receive the clamping nuts 11.

Attention is directed to the fact that the 10 edges of the wearing top or surface 4 are beveled to correspond with the bevel of the inclined flange 14, and by means of the elongated slots 10 the binding at the edges of the top 1 can be forced in forming contact 15 with the beveled edges of the wearing surfaces 4, and can be adjusted in the exact plane with each other and with the wearing surface 4 so that no sand-papering or other removing or finishing of either the edges of 20 the wearing surface 4 or of the binding need be sandpapered or otherwise removed to make a smooth and perfect surface between the binding and the wearing top and to bring the bindings at the several edges in 25 perfect alinement with each other.

In Fig. 4 I have shown a slight modification which consists in having the screw 8' pass from the inner side of the flange 2, instead of being carried by the head 7. In 30 this instance, the clamping member or head 7' is preferably made in an elongated bar placed within the grooves 5 and 6 of the binding and of a length shorter than the length of the binding so that the openings a 35 for the stem of the screw 8' may be tapped into the bar 7' through the elongated openings 10, when assembling the binding to the body or top 1. By making the bar 7' shorter than the binding, it will permit the binding 40 to be moved endwise independent of the bar 7' for properly positioning it. After it is positioned, then it is clamped into this position by means of the screw 8'. A still further slight modification is shown in Fig. 45 4, in that the lower edge of the flange 2 has an inwardly extending flange 2' which serves to strengthen and stiffen the top or body-portion 1, and will also serve as means through which the top or body-portion 1 50 can be connected with the other part of the furniture. I desire it also to be understood that the part referred to as the flange 2, may be simply the side of the desk or table, in which case the top or body 1, will be made as an integral part of the furniture.

Having thus described my invention, what I claim and desire to secure by Letters Patent is:

1. As an improvement in furniture, the 60 combination with a member having a flat surface and an inwardly extending flange, a covering for the flat surface, and a binding therefor having longitudinal grooves at the inner side of its upper and lower edges, a clamping member fitting in said grooves

and clamping means between the clamping member and the said flange for holding the said binding strip in place.

2. As an improvement in metal furniture, the combination with a member having a flat surface and having an extending flange, of a covering for the flat surface, and a binding therefor having a longitudinal groove at the inner side of its lower edge and a longitudinal groove at the inner side of its upper edge and means extending from the inner side of said flange and engaging the walls of the said grooves and clamping the said binding to the flange. 70 75

3. As an improvement in metal furniture, the combination of a member having a flat surface and an extending flange, a covering for the flat surface and a binding therefor having at the inner side of its lower edge an L-shaped flange and at the inner side of its upper edge a longitudinal groove with an inner tapered wall, the edge of the covering tapered to correspond with the said tapered wall and clamping means within the groove of the binding and between the binding and the said flange for clamping the said binding to said flange. 80 85 90

4. As an improvement in metal furniture, the combination with a member having a flat surface and a laterally extending flange, a covering for the said flat surface, and a binding comprising a strip having at the inner side of its lower edge a longitudinal groove, the upper edge turned inward at right angles and then tapered downward and outward, the edge of the covering tapered to fit the taper of the binding, a clamping member held by the turned in edges of the binding, and a clamping screw passing through the said flange and connecting the clamping member to the said flange. 95 100 105

5. As an improvement in metal furniture, the combination with a member having a flat surface and a laterally extending flange, a cover for the flat surface, and a binding having at the inner side of its lower edge a longitudinal groove and at the inner side of its upper edge a longitudinal groove, a clamping head movable in the said grooves, the said flange having an opening, the 110 clamping head carrying a screw with its stem end passing through the opening in the flange and a clamping nut upon the stem of the screw for clamping the binding against the said flange. 115 120

6. As an improvement in metal furniture, the combination with a member having a flat surface and a laterally extending flange, and a covering for the flat surface, of a binding, the lower edge of the binding having an inwardly extending L-shaped portion, and the upper edge of the binding turned inwardly at right-angles and tapered downwardly and outwardly the lower edge of the taper turned downward parallel with 125 130

the wall of the binding, a clamping member within the grooves formed at the edges of the binding, and clamping means between the clamping member and the said flange.

- 5 7. An improved binding for metal furniture consisting of an elongated strip having at one edge a laterally extending L-shaped portion, and at the opposite edge a laterally extended portion with a downwardly and outwardly inclined wall for the purpose described.

8. An improved binding for metal furniture, consisting of an elongated strip having

one edge bent laterally into an L-shaped portion and its other ends bent laterally on 15 the same side to form an outwardly and downwardly inclined wall with its lower edge extending parallel to the wall of the binding for the purpose described.

In testimony whereof I hereunto affix my 20 signature in the presence of two witnesses.

CARL OLSON.
